BUTTON FASTENER

Arthur Illsche, Rye, N. Y.

Application September 21, 1937, Serial No. 164,843

7 Claims. (Cl. 24—105)

This invention relates to fasteners of a type suitable for general use but specially designed, as herein embodied, for detachably securing buttons, ornaments and other articles to fabric and more particularly to wearing apparel and is a continuation, in part, of an application on which Letters Patent No. 2,127,363, were granted to me August 16, 1938.

In the patent referred to, the fastener consists of two members which are of frustro-conical form and screw-threaded for engagement one with the other, with the fabric interposed, without puncture, between them. The frustro-conical form given the members enables them to be securely engaged through fabrics of different thickness as represented, for example, by summer and winter weights of women's dress materials and avoids the necessity of producing the fasteners in different sizes for different thicknesses of material.

In the present embodiment of the invention, I again employ the frustro-conical feature, above referred to, to regulate engagement between the fastener members, according to the thickness of the fabric to which the button or the like is to be detachably secured.

As there may be objection to binding the fabric between the two screw-threaded fastener members, as above described, I have devised a form of fastener in which the engagement between the two screw-threaded members or their equivalent, operates a pair of clamp jaws which, in closing, attach the fabric securely to an eyelet of the button. In other words, the clamp serves as a substitute for the ordinary attaching thread used to sew the button to a garment and the opening and closing of the clamp is controlled by the screw-threaded members or their equivalent.

The above mentioned and other features of the invention will be explained at greater length in the detail description which follows:

In the accompanying drawing I have shown a form of fastener suitable for embodying my invention but do not wish to be understood as intending to limit myself to either the exact construction or arrangement illustrated, as various changes may be made therein without departing from the spirit and scope of the invention as outlined in the appended claims.

In the drawing:

Fig. 1 shows a form of the fastener in which the fabric is secured in an eyelet of the button (shown in section) by a two-member screw-threaded clamp.

Fig. 1a shows eyeleted buttons of the type

illustrated in Fig. 1, now in common use and well known in the art.

Fig. 2 is a cross section on the line s2, s2, of Fig. 1.

Fig. 3 is a view on an enlarged scale, showing the members of Fig. 1, in assembled relation, but separated somewhat for clearness of illustration, with parts appearing in section.

Fig. 4 shows a modification of the Fig. 1 form.

Fig. 5 shows a rearrangement of the Fig. 4 members with relation to the fabric.

Referring now to the drawing, I is a diagrammatic representation of a button, ornament or other article to be detachably secured to a fabric, indicated at 2.

In Figs. 1 to 3, inclusive, the button 1, provided on its underside with a fixed wire eyelet or loop 15, is a form well known in the art, and to bind the fabric in this eyelet or loop, I employ a clamp consisting of an approximately U or V-shaped member 16, having a pair of clamping jaws 17 at its upper end. The jaws are normally held separated by the spring action of the lower reduced portion 18 of the member and are closed by a threaded ring nut 19, engaging teeth 20 formed on opposite edges of the member.

It will be observed, that the threaded portion of the male member is reduced to strip form, extending lengthwise of the member, also that the taper given the threaded portion regulates the extent of engagement by the female member according to the thickness of the fabric caught between the clamp jaws, in the same manner as is done in my prior patent above referred to, by giving the members a frustro-conical form to accommodate different thicknesses of interposed fabric.

To secure the button to the fabric, the member 16, positioned on the opposite side of the fabric from the button, is pressed upward, against the eyelet or loop of the button with sufficient force to spring it into the same, with the fabric interposed between the engaged members, as shown in Fig. 3. The ring nut 19 is then screwed home on the member 16 to close the clamp jaws 17 within the button eyelet or loop and securely bind the fabric therein. To detach the button, the ring nut is unscrewed, the member 16, by a downward pull, is sprung off the button eyelet or loop and the button is freed.

The modification shown in Fig. 4 differs from that of Figs. 1 and 3, in having a pivoted lever, in the form of a clamp ring 21, substituted for the ring nut 19. The clamp ring 21 is pivoted at 22 in one of the jaws of the member 16 and

coacts with the tapered toothed edge 23 of the member 16, to close and open the jaws thereof. Here again, the taper given the toothed edge regulates the extent of engagement, according to 5 the thickness of the fabric held between the clamp jaws, as above explained with reference to Figs. 1 to 3, inclusive.

Fig. 5 shows the above described fastener (Fig. 4) positioned differently with respect to the fabric. In this figure the button and the fastener are on the outer side of the fabric and the member 16 is sewed fast to the fabric, as indicated at 10 24. In this arrangement, the clamp member engages the button eyelet or loop directly without having the fabric interposed between them.

As the use of the fastener and its many important advantages will be apparent from the foregoing, it will not be necessary to further describe the same.

20 Having described my invention, I claim:

1. A fastener for detachably securing an eyeleted button, ornament or other article to a fabric, comprising two engaging members one of which is provided with clamping jaws for engaging the eyelet of the button or the like through the fabric without puncturing or piercing the fabric, the last mentioned member being tapered to regulate engagement with the other fastener member according to the thickness of the fabric 25 and having a surface formation with which the other member cooperates to close the clamping jaws and maintain them closed upon the fabric in the eyelet of the button or the like.

2. A fastener for detachably securing an eyeleted button, ornament or other article to a fabric, comprising two engaging members one of which is provided with a pair of spring-held 30 clamping jaws adapted to be sprung into engagement with the eyelet of the button or the like with the fabric interposed without puncture between them, the last mentioned fastener member being tapered to regulate engagement with the other fastener member according to the thickness of the fabric, and having a surface formation with which the other member cooperates 35 to close the clamping jaws and maintain them closed upon the fabric in the eyelet of the button or the like.

3. A fastener for detachably securing an eyeleted button, ornament or other article to a fabric, comprising two engaging members one of which is provided with clamping jaws for engag- 40

ing the eyelet of the button or the like through the fabric without puncturing the fabric, the last mentioned member being tapered to regulate engagement with the other fastener member according to the thickness of the fabric, and having a surface formation with which the other member, in the form of a pivoted lever, cooperates to close the clamping jaws and maintain them closed upon the fabric in the eyelet of the button or the like. 10

4. A fastener for detachably securing an eyeleted button, ornament or other article to a fabric, comprising two engaging members one of which is provided with clamping jaws for engaging the eyelet of the button or the like through the fabric without puncturing or piercing the fabric, the last mentioned member being tapered to regulate engagement with the other fastener member according to the thickness of the fabric, the said member having a toothed 15 surface formation with which the other member, in the form of a ring pivoted to one of the clamping jaws, cooperates to close said jaws and maintain them closed upon the fabric in the eyelet of the button or the like. 20

25 5. A fastener comprising two cooperating members, one of the members being tapered and terminating at its larger end in spring clamping jaws, the said member having a surface formation on the tapered portion thereof engageable by the other member to close the clamping jaws, the last mentioned member being in the form of a ring pivoted to the member with which it cooperates.

30 6. A fastener comprising two cooperating members, one of the members being tapered and terminating at its larger end in spring clamping jaws, the said member having a surface formation on the tapered portion thereof engageable by the other member to close the clamping jaws, the last mentioned member being in the form of a ring pivoted to one of the jaws. 40

35 7. A fastener comprising two cooperating members, one of the members being tapered and terminating at its larger end in spring clamping jaws, the said member having a surface formation on the tapered portion thereof engageable by the other member to close the clamping jaws, the last mentioned member being in the form of a link pivoted to one of the jaws. 45
